GRINDING MACHINE

Millard Romaine, Cincinnati, Ohio, assignor to
Cincinnati Grinders Incorporated, Cincinnati,
Ohio, a corporation of Ohio

Application May 3, 1932, Serial No. 608,959

24 Claims. (Cl. 51—103)

This invention relates to improvements in machine tools and especially to improvements in grinding machines.

An object of the invention is the provision of an improved grinding machine of the centerless type particularly adapted for the grinding or finishing of comparatively large, heavy work pieces.

Another object of the invention is the provision of improved feeding mechanism for actuating one of the parts of a grinding throat to reduce the size of the said throat.

A further object of the invention is the provision of improved means for placing work pieces in the grinding throat and removing same therefrom.

A still further object of the invention is the provision of improved means for disposing work pieces into position on a work loading and ejecting mechanism and positioning said work pieces within a grinding throat and withdrawing same therefrom.

Other objects and advantages of the present invention should be readily apparent by reference to the following specification considered in conjunction with the accompanying drawings and it is to be understood that any modifications may be made in the exact structural details there shown and described within the scope of the appended claims without departing from or exceeding the spirit of the invention.

In the drawings:

Figure 1 is a side elevation of the improved centerless grinding machine embodying the improvements of this invention.

Figure 2 is a plan view of the machine disclosed in Figure 1 and as particularly seen by looking directly into the grinding throat thereof.

Figure 3 is a fragmentary sectional view through the feeding mechanism as seen particularly from line 3—3 on Figure 1.

Figure 4 is a view partly in elevation and partly in section as seen from line 4—4 on Figure 1.

Figure 5 is a fragmentary sectional view taken on line 5—5 or Figure 4.

Figure 6 is a sectional view taken on line 6—6 of Figure 5 showing a detail of the guide.

Figure 7 is a sectional view taken on line 7—7 of Figure 3.

Figure 8 is a fragmentary sectional view taken on line 8—8 of Figure 1.

Figure 9 is a fragmentary sectional view taken on line 9—9 of Figure 3.

Figure 10 is a diagrammatic illustration of the hydraulic circuit involved in the invention.

Figure 11 is a fragmentary sectional view taken on line 11—11 of Figure 2.

Throughout the several views of the drawings similar reference characters are employed to denote the same or similar parts.

The machine illustrated in the drawings may comprise a bed 15 having the base 16 from which rises a column terminating in an outwardly turned support 17 to which is secured a grinding wheel head 18 and outboard support 19. The head 18 has journaled therein a spindle 20 carrying a grinding wheel 21, which spindle 20 projects beyond the wheel 21 and is journaled in the outboard support 19. The support 17 has mounted thereon as at 22 a hood or cover 23 which substantially encloses the grinding wheel 21 for confining the coolant usual with grinding machines. The bed 15 further provides a suitable support 24 forming a dove-tailed guide 25 for guiding a truing mechanism 26 during its traverse across the active face of the grinding wheel 21.

The bed 15 has an operative inclined face extending at an acute angle to the base 16 to which is secured at a point adjacent the grinding wheel 21 a pair of brackets 27 in which are rotatably journaled stud shafts 28, see Figure 4. The stud shafts 28 are each received in a pair of lugs or ears 29 projecting downwardly from a bed plate 30 and which ears straddle the brackets 27. The bed plate 30 is provided on its upper surface with a dove-tailed guide 31 received in a similarly shaped guideway 32 formed on the under surface of a slide 33. The slide 33 in turn is provided with a dove-tailed guide 34 receiving a correspondingly shaped guideway 35 formed in the under surface of a slide 36. The slide 33 will hereinafter be termed the lower slide and the slide 36 the upper slide. The lower slide 33 is provided at its forward end with a block 37 in which is mounted a blade 38 having an operative inclined surface 39 inclining in the general direction of the regulating wheel surface and forming therewith a work receiving trough in which is positioned the work piece 40 during the grinding operation. The work 40 is further in peripheral contact with the operative face 39 of the blade 38 and takes the grinding thrust of the work while guiding and supporting it during the said grinding operation. In order to position the work on the blade to position the work with respect to the operative faces of the grinding and regulating wheels the block 37 has secured to one end thereof a bracket 41 having journaled in its one end a stud 42 to which is secured the inner race of an anti-friction bearing 43 carrying

ing the anti-friction end stop 44 that abuts against the flat terminal end of the work piece 40. As shown in the drawings, the work piece in this instance is a munition shell which is to have its shank portion cylindrically ground and finished.

The upper slide 36 has secured thereto or formed integral therewith a bracket 45 supporting a head 46 in which is journaled a spindle 47. The spindle 47 has secured to it a regulating wheel 48 adapted to engage the portion of the work being ground and through frictional engagement therewith control the rotation of the said work. For this purpose the regulating wheel 48 is rotated at a comparatively slow work rotation controlling rate of speed by means of a motor 49 which has secured to its shaft 50 a sprocket chain gear 51. Trained about the sprocket 51 is a gear chain 52 which is in turn trained about a similar sprocket 53 secured to a worm shaft 54 for rotating a worm 55 formed thereon or secured thereto. The worm 55 meshes with a worm wheel 56 secured to the regulating wheel spindle 47.

From the foregoing it will be noted that the grinding wheel and regulating wheel have their operative surfaces spaced from one another a distance to form a grinding throat that is subtended by the work rest blade. During the grinding operation the work is simultaneously in engagement with the grinding wheel, regulating wheel and work rest blade. The grinding wheel is rotated at a high grinding rate of speed to effect a stock removal from the work while it is peripherally supported by the angle top of the work rest blade and the rotation of the work is frictionally controlled through its engagement with the regulating wheel.

In order to feed the work into the grinding wheel the bed plate 30 is formed at its end opposite to that from which the lugs 29 project with ears 57 and 58 having formed therein in axial alignment perforations receiving a pivot pin 59. Supported by the pivot pin 59 is a clevice 60 receiving in a threaded perforation therein one end of a push rod 61 which extends transversely of the bed terminating in a feed box 62 secured to the rear of the bed 15 and shown in detail in Figure 3. The feed box 62 may be secured to the bed in any desirable manner, here shown as by means of bolts 63. The rear wall of the bed 15 and the adjacent wall of the feed box 62 have formed through them in axial alignment a perforation in which is mounted a guide bushing 64 that encircles a reduced portion 65 of the feed rod 61. The bushing 64 has projecting from it fingers 66 through which extends a pin 67 having mounted thereon an anti-friction roller 68 straddled on opposite sides by the fingers 66. The roller 68 contacts with the inclined wedge cam face 69 of a wedge cam feed member 70. Diametrically opposed to the cam face 69, the feed member 70 is provided with a slot 71 providing a flat true face 72 in contact with the anti-friction roller 73 mounted on a pin 74 carried by fingers 75. The fingers 75 are joined at their rear ends by means of a plug member 76 that is secured in the rear wall of the feed box housing 62 to align the anti-friction roller 73 with the anti-friction roller 68 to engage the feed member 70 therebetween.

The feed member 70 has secured to its one end one end of a piston rod 77 which passes through a stuffing box 78 forming one head for a cylinder 79 and whereby the said cylinder is secured to one of the lateral sides of the feed box 62 so that said cylinder may project beyond the said box. Enclosed within the cylinder 79 is a piston 80 secured to the end of the rod 77 within the cylinder

79. The other end of the cylinder 79 is closed by a cylinder head 81. The piston 80 is actuated relative to the cylinder 79 by means of hydraulic pressure for shifting the feed member 70 relative to the rollers 68 and 73, which due to the inclined wedge face of the member 70 axially adjusts or actuates the push rod 61 and oscillates the bed plate 30 about the pivot studs 68 and thereby feeds the work carried by the blade into the grinding wheel.

For introducing pressure to the opposite ends of the cylinder 79 the stuffing box or cylinder head 78 has formed therein a port 82 to which one end of a pipe or conduit 83 is secured. Similarly the piston head 81 has formed therein a port 84 for one end of a pipe or conduit 85. The other ends of the pipes 83 and 85 respectively terminate at ports 86 and 87 formed in a casing 88 that encloses a valve sleeve 89 having ports therein which register with the ports 86 and 87. The valve casing 88 is further provided with ports 90, 91 and 92 respectively in alignment with the ends of pipes or conduits 92a, 93 and 94 which are respectively exhaust, infeed and exhaust conduits. As shown diagrammatically in Figure 10, the pressure conduit 93 is connected at its other end with a pump 95 adapted to take oil through suction pipe 96, contained in tank or sump 97, and discharge same under pressure into the said pressure line 93. The pipes or conduits 92a and 94 are joined in a single exhaust or return line 98 that terminates in the tank 97 for returning the spent hydraulic medium or oil to the tank or sump 97.

In order to alternately connect the pressure line 93 with the lines 83 and 85, the valve sleeve 89 has mounted interiorly thereof a valve 99 having heads 100, 101 and 102 formed thereon for providing reduced portions therebetween. As shown in Figure 10, the pressure line 93 is connected with the pipe or conduit 83 for delivering the hydraulic medium to the left hand face of the piston 80 thereby driving said piston to the right carrying with it the member 70. Simultaneously the pipe or conduit 85 is connected with the pipe or conduit 94 for delivering the hydraulic medium ahead of the piston 80 to the tank or sump 97. It will be readily evident that by shifting the valve 99 to the right, as seen in Figures 3 and 10, the pressure in the conduit 93 will be cut off by means of the valve head 100 from the conduit 83 and connected with the conduit 85 thereby causing the pressure to act on the right hand face of the piston 80 for driving the same to the left. Simultaneously with the movement of the valve 99 the head 100 will connect the conduit 83 with the exhaust pipe or conduit 92a and thereby deliver the hydraulic medium to the tank or sump 97.

As seen in Figure 3, the valve 99 has projecting from its right hand end a bar or extension 104 which is in axial alignment with an adjustable bumper 105 projecting from the adjacent end of the feed member 70. The bumper 105 conveniently takes the form of a bolt being provided with a lock nut 106 for securing the bolt in adjusted position. The bumper 105 is adjusted in axial position for engaging the end of rod 104 and shifting the valve 99 to the left to thereby automatically effect reverse actuation of the piston 80. It will be understood that the movement of the valve 99 to the left will gradually cut off the flow of medium through the port 87 and, unless the momentum is considerable, will eventually stop the flow through the port 87 and stop further

movement of the said valve and consequently further movement of the piston 80. To avoid this, the valve, as seen in Figure 9, is provided with a pair of cam grooves 107 and 108 each having 5 their side walls inclined and co-operating with a spring pressed load and fire dog 109. From this it will be seen that it is only necessary to shift the valve 99 an amount sufficient to cause the cam point of the load and fire dog 109 to ride 10 up the intermediate wall of the grooves 107 and 108 which compresses or loads the spring 110 of the dog 109. As soon as the apex of the said inclined wall is reached, the spring expands or fires the dog 109 which through co-operation of its cam point and the cam or inclined 15 wall of the groove 107 completes the shifting of the valve 99 in the proper direction.

To shift the valve 99 to the right, it is provided on its left hand end with a head 111 adapted to be engaged by a roller 112 rotatably mounted in one end of a bell crank 113 pivoted at the junction of its arms at 114 to a bracket 115 projecting from the lateral side of the feed casing 62. The other arm of the bell crank 113 is pivoted 25 at 116 to one end of a valve actuating rod 117 extending along the side of the bed to the front end thereof. The rod 117 as seen in Figure 1, has its other end pivotally connected at 118 to an arm 119. The arm 119 is part of a bell crank having 30 integral therewith the arm 120 which forms a foot treadle 121. The arms 119 and 120 are pivoted at 122 to a suitable portion of the base 16. A spring 123 has its one end secured to the arm 119 and its other end anchored to the bed 15 for 35 oscillating the foot treadle 121 in a counter-clockwise direction and thereby keeping the said treadle elevated and the roller 112 out of reach of the valve 99 as it is shifted by the member 70 and load and fire dog.

From the foregoing it will be noted that in order to feed the work into the grinding wheel after it is mounted on the blade, it is simply necessary for the operator to depress the foot treadle 121 for shifting the valve 99 to the right as seen 40 in Figure 3. It is to be understood that at this time the piston is at the other end of the cylinder 79 from that shown in Figure 3 so that the bumper 105 is remote from the end 104 of the valve 99. It is also to be understood that it is 45 only necessary to shift the valve 99 to the right a sufficient distance to cause the load and fire dog to rise to the apex of the inclined cam grooved walls whereupon the said dog will complete the shifting of the valve. As soon as the 50 valve has been shifted the piston 80 starts toward the left thereby shifting the feed member 70 in a corresponding direction. The inclined wedge face 69 which, as shown in Figure 3, inclines downwardly from the left hand end thereof, gradually as 55 forces the roller 68 outwardly, or to the right, as seen in Figure 1, thereby through the rod 61 oscillating the bed plate and the parts carried thereby about the axis of the pivot shafts 28. This feeding of the work into the grinding wheel continues 60 until the end of the feed member or the bumper 65 105, carried thereby, engages the valve rod 104 for shifting same to the left and connecting the hydraulic medium with the left hand face of the piston 70 for retracting said piston as above described.

In order to take up for wheel wear and to compensate for the truing of the operative surfaces of both the grinding wheel 21 and regulating wheel 48, the bed plate 30 has journaled thereon 75 as by means of a bracket 124 an adjusting screw

125. The screw 125 has in threaded engagement therewith a nut 126 having formed on its outer surface a spiral gear 127 meshing with a spiral gear 128 on the end of a transverse shaft 129. The nut 126 and shaft 129 are rotatably mounted against axial movement in the upper slide 36, the latter being carried on anti-friction bearings mounted in lugs or arms 130 projecting upwardly from the said slide 36. The outer end of the shaft 129 has secured to it a bevel gear 131 meshing with a bevel gear 132 secured to the lower end of a vertical shaft 133 journaled in a sleeve bracket 134 mounted on the bracket 45 of the upper slide 36. The bracket 134 has journaled therein the micrometer adjusting mechanism which terminates in a hand crank 135 and the hand wheel 136 as is usual in cross feed adjusting mechanisms. In order that the slides may be independently and jointly actuated, they are respectively provided with a clamp 137 and 138, the former being associated with the lower slide whereby it may be clamped to the base plate while the upper slide is adjusted relative thereto, and the latter being carried by the upper slide for securing same to the lower slide which upon release from the base plate permits the unitary actuation or adjustment of the slides. The foregoing manually operated mechanism is also utilized for initial set up of the parts of the machine.

To assist in the changing of the wheels, which are of a considerable width and weight, the bed or column 15 has projecting from its rear wall a bracket 139 forming a swivel base and receiving the reduced end 140 of a bar 141. The bar 141 passes through a bearing 142 on the end of an arm 143 carried by the upper or gooseneck end of the bed or column 15. Secured to the upper end of the bar 141 is a beam 144 which may conveniently take the form of an iron I-beam for forming tracks and guide for a trolley 145 mounted thereon. The trolley 145 has a hook 146 associated therewith. The operation of the crane just described is readily apparent from an inspection of Figure 1.

The work, as noted above, is a munition shell and is of considerable weight making it next to impossible to manually dispose the work in position for mounting in the grinding throat, wherefor there is provided a conveyor for delivering the work to the machine. Any type of conveyor may be employed, but as here shown it conveniently takes the form of a pair of angle irons 147 and 148 each having one of its legs disposed in opposition to the other, being supported a sufficient distance apart and carrying a plurality of roller pins or shafts 149. The said pins or shafts 149 each support a freely rotating roller or barrel 150 upon which the work is mounted and manually actuated or moved, which work, due to the roll or rotation thereof is transferred from one roller 150 to the next.

In alignment with the throat of the machine, as particularly shown in Figure 1, there is provided a frame comprising side members 151 and 152 being joined at their outer ends by a brace or bracket 153 and having their inner ends respectively secured to brackets 154 secured to the upper slide at a point adjacent the work rest block 37. The brace 153 has secured to its under surface a furcated bracket 155 having aligned apertures 70 in its arms through which a pivot pin 156 extends. Encircling the pin 156 is the eye of a strut or brace 157 having its lower end threaded as at 158 and received in a nut 159. The nut 159 has integral therewith a hand wheel 160 whereby the 75

said nut is rotated and the nut rests on a swivel member 161 swiveled in the bracket 162 which rests on the base or support for the machine base 16. From this it will be noted that the frame 151 and 152 is adapted to be adjusted as respects the bed of the machine and the upper and lower slides to at all times maintain the proper relationship between the work and wheels.

The frame 151—152 supports a work loading 10 and ejecting slide 163 adapted to be positioned at the upper end of the frame for receiving the work and carrying same into the grinding throat. The slide 163 is provided on opposite sides with rack member 164 meshing with a pinion 165 secured to a shaft 166 journaled in the frames 151 and 152. The shaft 166 has secured to it exteriorly of the frame member 152 a hand wheel 167 whereby the said shaft is rotated for causing the slide to be traversed from its outer work receiving position to a position within the grinding throat. The slide 163 has the rack members 164 connected by a bridge 168 to which is pivoted an L-shaped lever 169, the pivot 170 passing through the lever at the juncture of the legs of said lever. 20 The leg 171 of the lever 169 is provided with a counterbore 172 and reduced perforation 173 in axial alignment with the counterbore 172. The stud 174 has one end threaded into the bridge 168 and passes through the counterbore 172 and 30 aligned perforation 173 and receives lock nuts 175 on the end exteriorly of the leg 171. A spring 176 encircles the stud 174 abutting on one end with the bridge 168 and on the other end with the base of the counterbore 172. The other leg 35 177 of the lever 169 carries a pivot 178 for a roller 180 which is adapted to be held in contact with the work during the actual grinding operation.

The lower end of the slide 163 is provided with 40 a cross strut 181 having its upper surface 182 formed at an angle to the direction of extent of the slide 163. The strut 181 has let into it a plurality of roller studs 183 each being encircled by a roller 184 and supporting the work against 45 the yielding urge of the spring 176 and roller 180 prior to the engagement of the work with the angle top 39 of the work rest blade 38.

To assist in mounting the work on the slide 163 and for transferring same from the conveyor 50 to the said slide, the frame members 151 and 152 are joined intermediate their ends by a block 185 having arms 186 and 187 projecting upwardly therefrom on opposite sides thereof. A plurality of studs 188 and 189 are respectively carried by 55 the sides 186 and 187 and between each pair of opposed studs 188 and 189 is disposed a roller 190 which is in alignment with the work conveyor and receives the work from the conveyor rollers 150 for positioning it between the pressure roller 180 and the carrying rollers 184.

To hold the slide in its inner and outer positions it is provided with a pair of slots 191 and 192 adapted to individually co-operate with a latch 193 formed on one surface of a lever 194 pivoted at 195 to the frame member 152. The notch 191 receives the latch 193 when the slide 163 is in its inner position, as shown in Figure 5, and prevents any movement of the slide during the grinding operation. In order to withdraw the work from the grinding throat the latch 193 is lifted from the slot 191 and the hand wheel 167 actuated in a clockwise direction, as seen in Figure 5, thereby shifting the slide 163 to the right until the notch 192 is aligned with 75 the latch 193 whereupon the latch 193 is disposed

within the said notch for holding the slide in position to receive a work piece from the conveyor rolls 150 and indicated by the dotted work piece 196 in Figure 5.

What is claimed is:

1. In a grinding machine the combination with a bed, a grinding wheel rotatably mounted thereon, a work support, and means pivotally securing the work support to the bed, of means longitudinally actuatable for oscillating the work support about its pivotal mounting for feeding the work into the grinding wheel, said means comprising a wedge-shaped cam, a follower for the cam, a connection between the follower and work support, and hydraulically actuatable means for axially adjusting the wedge-shaped cam. 10

2. In a grinding machine the combination with a bed, a grinding wheel rotatably mounted thereon, and a work support pivotally connected to the bed for oscillation toward and from the grinding wheel, of hydraulically actuatable means for oscillating said work support including a valve, and foot treadle control means for shifting the valve in one direction to oscillate the work support toward the grinding wheel. 20

3. In a grinding machine the combination with a bed, a grinding wheel rotatably mounted thereon, and a work support pivotally connected to the bed for oscillation toward and from the grinding wheel, of hydraulically actuatable means for oscillating said work support including a valve, foot treadle control means for shifting the valve in one direction to oscillate the work support toward the grinding wheel, and automatic means for shifting the valve in the other direction. 30

4. In a grinding machine of the class described the combination with a bed, a grinding wheel rotatably supported thereby, and a work support pivotally mounted on the bed for oscillation toward and from the grinding wheel, of a wedge-shaped cam, an operative connection between the cam and the work support, an hydraulically actuated piston for reciprocating the cam and thereby oscillating the work support, an hydraulic medium for actuating the piston, a valve controlling the flow of the medium, and a foot treadle for shifting the valve in one direction. 40

5. In a grinding machine of the class described the combination with a bed, a grinding wheel rotatably supported thereby, and a work support pivotally mounted on the bed for oscillation toward and from the grinding wheel, of a wedge-shaped cam, an operative connection between the cam and the work support, an hydraulically actuated piston for reciprocating the cam and thereby oscillating the work support, an hydraulic medium for actuating the piston, a valve controlling the flow of the medium, a foot treadle for shifting the valve in one direction, and means carried by the cam for actuating the valve in the other direction to reverse the flow of the hydraulic medium. 50

6. In a grinding machine of the class described the combination with a bed, a grinding wheel rotatably supported thereby, and a work support pivotally mounted on the bed for oscillation toward and from the grinding wheel, of a wedge-shaped cam, an operative connection between the cam and the work support, an hydraulically actuated piston for reciprocating the cam and thereby oscillating the work support, an hydraulic medium for actuating the piston, a valve controlling the flow of the medium, a foot treadle for shifting the valve in one direction, means 60

carried by the cam for actuating the valve in the other direction to reverse the flow of the hydraulic medium, and a load and fire mechanism operable upon shifting of the valve for completing its movement when actuated by the valve actuator on the cam.

7. In a centerless grinder of the class described the combination with a bed, a grinding wheel rotatably mounted thereon for rotation at a high grinding rate of speed, an opposed regulating wheel rotatable at a relatively slow work rotation controlling rate of speed, the grinding and regulating wheels forming a grinding throat therebetween, a work rest blade subtending the grinding throat, and means pivotally supporting the work rest blade and regulating wheel on the bed for oscillation toward and from the grinding wheel, of hydraulically actuatable means for effecting the oscillation of the work support and regulating wheel, said means comprising a wedge cam adapted to be axially adjusted, and an hydraulically actuated piston associated with the cam for actuating same.

8. In a centerless grinder of the class described the combination with a bed, a grinding wheel rotatably mounted thereon for rotation at a high grinding rate of speed, an opposed regulating wheel rotatable at a relatively slow work rotation controlling rate of speed, the grinding and regulating wheels forming a grinding throat therebetween, a work rest blade subtending the grinding throat, and means pivotally supporting the work rest blade and regulating wheel on the bed for oscillation toward and from the grinding wheel, of hydraulically actuatable means for effecting the oscillation of the work support and regulating wheel, said means comprising a wedge cam adapted to be axially adjusted, an hydraulically actuated piston associated with the cam, an hydraulic medium for actuating the piston, a valve controlling the flow of the medium, and foot treadle means for actuating the valve for initiating a movement of the piston and wedge cam to effect the oscillation of the work and regulating wheel toward the grinding wheel.

9. In a centerless grinder of the class described the combination of a pair of opposed grinding and regulating wheels forming a grinding throat therebetween, means supporting one of said wheels for oscillatory movement toward and from the other, a work rest blade subtending the grinding throat, a slide movable laterally of the grinding throat for disposing a work piece on and removing same from the blade, carrier rolls supported by the slide to facilitate mounting of the work on the slide, a yieldable pressure roll on the slide for yieldably holding the work in contact with the blade, and means for shifting the slide into and out of the grinding throat.

10. In a centerless grinder of the class described the combination of a pair of opposed grinding and regulating wheels forming a grinding throat therebetween, means supporting one of said wheels for oscillatory movement toward and from the other, a work rest blade subtending the grinding throat, a slide movable laterally of the grinding throat for disposing a work piece on and removing same from the blade, carrier rolls supported by the slide to facilitate mounting of the work on the slide, a yieldable pressure roll on the slide for yieldably holding the work in contact with the blade, means for shifting the slide into and out of the grinding throat, a frame slidably supporting the slide, rollers on the frame adapted to be aligned with the slide when the slide is in

its withdrawn position, and means carried by the frame co-operating with the slide for holding it in its withdrawn and loading positions.

11. In a centerless grinder of the class described the combination of a bed, a grinding wheel rotatably mounted thereon, an opposed regulating wheel, the grinding and regulating wheels forming a grinding throat between them, a work rest blade subtending the grinding throat, means for supporting one of the wheels for adjustment relative to the other and relative to the work rest blade, means for supporting the work rest blade for adjustment relative to the bed and the grinding and regulating wheels, means pivotally attaching the wheel and work rest blade supporting means to the bed for oscillation relative thereto, and hydraulically actuated mechanism having an operative connection with the pivotal connecting means for effecting the oscillation of said wheel and work rest blade.

12. In a centerless grinder of the class described the combination of a bed, a grinding wheel rotatably mounted thereon, an opposed regulating wheel, the grinding and regulating wheels forming a grinding throat between them, a work rest blade subtending the grinding throat, means for supporting one of the wheels for adjustment relative to the other and relative to the work rest blade, means for supporting the work rest blade for adjustment relative to the bed and the grinding and regulating wheels, means pivotally attaching the wheel and work rest blade supporting means to the bed for oscillation relative thereto, and hydraulically actuated mechanism having an operative connection with the pivotal connecting means for effecting the oscillation of said wheel and work rest blade including a reciprocable wedge type cam, a piston connected with the cam, and a valve controlling an hydraulic medium for actuating the piston.

13. In a centerless grinder of the class described the combination of a bed, a grinding wheel rotatably mounted thereon, an opposed regulating wheel, the grinding and regulating wheels forming a grinding throat between them, a work rest blade subtending the grinding throat, means for supporting one of the wheels for adjustment relative to the other and relative to the work rest blade, means for supporting the work rest blade for adjustment relative to the bed and the grinding and regulating wheels, means pivotally attaching the wheel and work rest blade supporting means to the bed for oscillation relative thereto, and hydraulically actuated mechanism having an operative connection with the pivotal connecting means for effecting the oscillation of said wheel and work rest blade including a reciprocable wedge type cam, a piston connected with the cam, a valve controlling an hydraulic medium for actuating the piston, and means for placing a work piece on the work rest blade and withdrawing same therefrom including a slide laterally shifted relative to the grinding throat.

14. In a centerless grinder of the class described the combination of a bed, a grinding wheel rotatably mounted thereon, an opposed regulating wheel, the grinding and regulating wheels forming a grinding throat between them, a work rest blade subtending the grinding throat, means for supporting one of the wheels for adjustment relative to the other and relative to the work rest blade, means for supporting the work rest blade for adjustment relative to the bed and the grinding and regulating wheels, means pivotally attaching the wheel and work rest blade

- supporting means to the bed for oscillation relative thereto, and hydraulically actuated mechanism having an operative connection with the pivotal connecting means for effecting the oscillation of said wheel and work rest blade including a reciprocable wedge type cam, a piston connected with the cam, a valve controlling an hydraulic medium for actuating the piston, and means for placing a work piece on the work rest blade and withdrawing same therefrom including a slide laterally shifted relative to the grinding throat, and conveyor means for conveying the work pieces to the slide.
15. In a grinding machine of the class described the combination with a bed, and a wheel head pivotally mounted thereon for oscillation relative thereto, of an axially shiftable member having a cam face thereon for movement relative to the wheel head, means between the cam face and wheel head for effecting oscillation of said wheel head as the member is moved, and hydraulic means for axially actuating the member.
16. In a grinding machine the combination with a bed, and a wheel head pivotally mounted on the bed for oscillation relative thereto and including a slide for adjusting the wheel head relative to its pivotal mounting, of hydraulically actuatable means carried by the bed for movement relative thereto for oscillating the wheel head.
17. In a centerless grinder of the class described the combination of a column having an operative supporting portion disposed in a substantially vertical plane, a grinding wheel rotatably supported by the column at one end of the supporting portion, an oscillatable support pivotally secured to the supporting portion of the column, a slide on the support, a regulating wheel rotatably mounted on the slide in opposition to the grinding wheel and forming therewith a grinding throat, means for actuating the slide relative to the support toward the grinding wheel to vary the size of the grinding throat, and means for actuating the support and slide about the pivotal connection of the slide toward and from the grinding wheel to effect a stock removal from the work within the throat.
18. In a centerless grinder of the class described the combination of a column having an operative supporting portion disposed in a substantially vertical plane, a grinding wheel rotatably supported by the column at one end of the supporting portion, an oscillatable support pivotally secured to the supporting portion of the column, a slide on the support, a regulating wheel rotatably mounted on the slide in opposition to the grinding wheel and forming therewith a grinding throat, means for actuating the slide relative to the support toward the grinding wheel to vary the size of the grinding throat, means for actuating the support and slide about the pivotal connection of the slide toward and from the grinding wheel to effect a stock removal from the work within the throat, and a work rest sub-tending the grinding throat peripherally supporting a work piece while disposed within the throat.
19. In a centerless grinding machine of the class described the combination of a vertically disposed column having a supporting portion disposed in a plane forming an obtuse angle with the horizontal, a grinding wheel rotatably secured to the column at one end of the supporting portion of the column, a work rotation and control mechanism on the column and including a regulating wheel opposed to the grinding wheel and forming a grinding throat there between, means pivotally securing the work rotation and controlling mechanism to the supporting portion of the column, hydraulic means for effecting an oscillation of the work supporting and controlling mechanism toward and from the grinding wheel and including a control valve therefor, manual means for actuating the valve in one direction to effect an oscillation of the work controlling and supporting mechanism toward the grinding wheel, and automatic means for shifting the valve in the opposite direction and effecting an opposite oscillation of the mechanism.
20. In a centerless grinding machine of the class described the combination of a vertically disposed column having a supporting portion disposed in a plane forming an obtuse angle with the horizontal, a grinding wheel rotatably secured to the column at one end of the supporting portion of the column, a work rotation and control mechanism on the column and including a regulating wheel opposed to the grinding wheel and forming a grinding throat there between, means pivotally securing the work rotation and controlling mechanism to the supporting portion of the column, hydraulic means for effecting an oscillation of the work supporting and controlling mechanism toward and from the grinding wheel and including a control valve therefor, a pivotally mounted foot treadle associated with the machine, a connection between the treadle and valve whereby the valve is actuated in one direction by the foot treadle to effect an oscillation of the work supporting and controlling mechanism toward the grinding wheel, and automatic means for reversely shifting the valve and effecting a reverse actuation of the mechanism.
21. In a centerless grinder of the class described the combination of a bed, a pair of opposed grinding and regulating wheels forming a grinding throat there between, a work support sub-tending the grinding throat and peripherally engaging the work during the grinding operation, a slide shiftable laterally of the grinding throat for placing work within the throat and removing same therefrom, work engaging means on the slide for engagement with the work during the movement of the slide into and from the throat, said means comprising rollers rotatable about axes at right angles to one another whereby the work engages a roller rotatable in a direction in which the work is shifted while being positioned on and removed from the slide and whereby the work is engaged by a roller rotatable in the direction of rotation thereof during the grinding operation, means pivotally mounting the last mentioned roller for oscillation toward and from the work, and yielding means for shifting said last mentioned roller toward the work to maintain contact of the work with the peripheral support during the grinding operation.
22. In a centerless grinder of the class described the combination of a bed, a pair of opposed grinding and regulating wheels forming a grinding throat therebetween, a work support sub-tending the grinding throat and peripherally engaging the work during the grinding operation, a slide shiftable laterally of the grinding throat for placing work within the throat and removing same therefrom, work engaging means on the slide for engagement with the work during the movement of the slide into and from the throat, said means comprising rollers rotatable about axes at right angles to one another whereby the work engages a roller rotatable in a direction in which the work is shifted while being positioned on and removed from the slide and whereby the work is engaged by a roller rotatable in the direction of rotation thereof during the grinding operation.

rection in which the work is shifted while being positioned on and removed from the slide and whereby the work is engaged by a roller rotatable in the direction of rotation thereof during the 5 grinding operation, means pivotally mounting the last mentioned roller for oscillation toward and from the work, yielding means for shifting said last mentioned roller toward the work to maintain contact of the work with the peripheral support during the grinding operation, a supporting 10 frame for the work slide, means for actuating the slide relative to the frame from a position outside of the grinding throat to a position within said throat, and rollers carried by the frame at 15 the point where the slide is outside of the grinding throat for effecting a shifting of the work on the slide.

23. In a centerless grinder of the class described the combination of a bed, a pair of opposed grinding and regulating wheels forming a grinding throat there between, a work support sub-tending the grinding throat and peripherally engaging the work during the grinding operation, a slide shiftable laterally of the grinding 20 throat for placing work within the throat and removing same therefrom, work engaging means on the slide for engagement with the work during the movement of the slide into and from the throat, said means comprising rollers rotatable 25 about axes at right angles to one another whereby the work engages a roller rotatable in a direction in which the work is shifted while being positioned on and removed from the slide and

whereby the work is engaged by a roller rotatable in the direction of rotation thereof during the grinding operation, means pivotally mounting the last mentioned roller for oscillation toward and from the work, yielding means for shifting said last mentioned roller toward the work to maintain contact of the work with the peripheral support during the grinding operation, a supporting frame for the work slide, means for actuating the slide relative to the frame from a position outside of the grinding throat to a position within said throat, rollers carried by the frame at the point where the slide is outside of the grinding throat for effecting a shifting of the work on the slide, and conveyor means in line with the frame rollers for conveying work pieces thereto and therefrom.

24. In a machine tool organization the combination of a bed, a tool support, a work support, means pivotally connecting one of said supports to the bed for oscillation relative thereto toward and from the other, cam means for effecting the oscillation of said support, a hydraulic motor for actuating the cam, a hydraulic circuit for controlling the movement of the motor including a 25 control valve, manual means for shifting the valve in one direction, yielding means for shifting the said valve in the other direction, means for latching the valve in the position effected by the manual means, and automatically operable 30 means for unlatching the valve to permit its operation by the yielding means.

MILLARD ROMAINE.
